DUPLEX BRAKE

Carl E. Tack, Chicago, Ill., assignor to American Steel Foundries, Chicago, Ill., a corporation of New Jersey

Application January 30, 1943, Serial No. 474,113

23 Claims. (Cl. 188—33)

My invention relates to brake rigging and more particularly to a type of railway brake rigging sometimes called "Duplex" or "Duo-Simplex" in which each wheel is braked by a friction shoe engaging the periphery thereof as well as by shoes engaging the inboard and outboard sides thereof.

My invention comprehends an arrangement in which one or more of the friction shoes is formed of iron and other of said shoes are formed of composition in order to obtain a combination of the torque characteristics of iron and composition shoes in combination with an iron wheel.

An object of my invention is to obtain equalized heating of the wheels by braking the sides as well as the periphery thereof in the manner above described, said equalized heating reducing the tendency of the wheels to crack as a result of thermal stresses due to braking forces thereon.

Another object of my invention is to design a "Duplex" brake arrangement of the generic type disclosed in the co-pending application Serial No. 439,370, filed April 17, 1942, in the United States Patent Office in the names of Carl E. Tack and Wesley A. Helsten, in which live and dead truck levers serve as actuating means for the friction shoes, said levers being in turn actuated by interconnected live and dead cylinder levers connected to opposite ends of truck-mounted power cylinders in what is generally termed a unit cylinder arrangement.

In the present invention the friction shoes at corresponding sides of the truck are actuated through brake beams connected to the truck levers and extending transversely of the truck, one of the beams associated with each wheel extending above the axle level and the other beam associated with said wheel extending below the axle level.

Another object of the present invention is to design a brake rigging such as above described in which one of the truck levers associated with each wheel is operatively connected to an equalizer lever having operative engagement at opposite ends thereof with a pair of bell crank levers supported from the truck frame and carrying friction shoes for engagement with inboard and outboard sides of the adjacent wheel as above described.

In the drawings,

Figure 1 is a top plan view of a railway car truck embodying my invention, and Figure 2 is a side elevation of the structure shown in Figure 1.

Figure 3 is a fragmentary end view taken from

the right as seen in Figures 1 and 2, and Figure 4 is a sectional view taken in the planes indicated by the line 4—4 of Figure 2.

In each of said figures certain details may be omitted where they are more clearly seen in other views.

Describing my invention in detail, the truck frame generally designated 2 comprises the side rails 4, 4, the end rails 6, 6 and the spaced transoms 8, 8 between which a load carrying member or bolster (not shown) may be suspended in the usual manner. Each side rail at each end thereof is formed with a pair of spaced pedestal legs 10, 10 adapted for the reception therebetween of a journal box (not shown) formed and arranged for the accommodation of the adjacent end of the associated wheel and axle assembly fragmentarily indicated at 12.

At opposite sides of each wheel are disposed the live and dead truck levers 14 and 16, the dead truck lever being pivotally fulcrumed at its upper end as at 18 from a bracket 20 which may be formed on or secured in any convenient manner to the truck frame. The corresponding dead levers 16, 16 at opposite sides of the truck are pivotally connected intermediate their ends as at 22, 22 respectively to the brake beams 24, 24, and each dead lever is operatively associated at its lower end with friction means for engaging inboard and outboard surfaces of the adjacent wheel as hereinafter more fully described.

Each beam 24 is pivotally connected at 26 adjacent each end thereof to one end of a pull rod 28, the opposite end of said rod being pivotally connected at 30 to the adjacent live lever 14. The lower ends of corresponding live levers 14, 14 at opposite sides of the truck are pivotally connected at 32, 32 to fulcrum jaws 34, 34 on the brake beams 36, 36 extending transversely of the truck in the usual manner, each beam being provided with a jaw 38 pivotally connected at 40 to the lower end of a brake hanger 42, the upper end of said hanger being pivotally connected at 44 to the hanger bracket 46 of usual form, said bracket being secured at 48 to the adjacent transom 8. Each end of each beam 36 is provided with a trunnion 50 (Figure 1) for pivotal engagement with a brake head 52 in the usual manner, said brake head carrying a brake shoe 54 for engagement with the periphery of the adjacent wheel and said head being afforded additional support in the usual manner by means of a brake hanger 56 pivotally connected at 58 to the bracket 60 on the truck frame.

The lower end of each dead truck lever 16 is

pivots connected at 62 to a link 64 which is in turn pivotally connected at 66 to an equalizer lever 68 afforded slidable support adjacent opposite ends thereof from spaced inclined ledges 70, 70 formed on the fulcrum casting 72, which may be secured as by welding at 74 (Figure 2) to the adjacent end rail 6. The equalizer lever 68 abuts at 76, 76 the arcuate corresponding ends of a pair of bell crank levers 78, 78, said levers being afforded pivotal fulcrums at 80, 80 from the fulcrum casting 72 and said levers carrying on opposite corresponding ends thereof the brake shoes 82, 82 for engagement with inboard and outboard surfaces on the adjacent wheel. Release means for the bell crank levers 78, 78 is provided in the form of tension springs 84, 84 underlying the equalizer lever 68 and pivotally connected at opposite ends thereof as at 86, 86 to the respective bell crank levers and at 88, 88 to the wing portions 90, 90 on the fulcrum casting 72. It may be noted that the casting 72 may be afforded a torque connection to the truck frame by means of a flange 92 on the top thereof, said flange being pivotally connected at 94 to the hanger 96 which is pivotally connected at 98 to the truck frame.

It may also be noted that the bell crank levers 78, 78 associated with each wheel and the cooperating equalizer lever 68 lie in a plane diagonal with respect to the horizontal and approximately bisecting the axis of said wheel, although it will be understood that, if desired, said levers may be disposed in a horizontal plane.

Actuating means for the rigging at each side of the truck may be provided in the form of a power cylinder 100 mounted at 102, 102 on a cylinder pad 104 on the truck frame, the piston rod 106 projecting from one end of said cylinder being pivotally connected at 108 to the outer end of the live cylinder lever 110, said cylinder lever being pivotally connected intermediate its ends as at 112 to a pull rod 114, and said cylinder lever 110 being pivotally connected at its inner end as at 116 to a pull rod or link 118 afforded pivotal connection at 120 to the upper end of the adjacent live truck lever 14.

The pull rod 114 is pivotally connected at its opposite end as at 122 to the dead cylinder lever 124 intermediate its ends, said rod being provided with a manual slack adjuster 126 of usual form. The outer end of the dead cylinder lever 124 is pivotally connected at 128 to the automatic slack adjuster means 129 secured at 130, 130 to the cylinder 100, and the inner end of the dead cylinder lever 124 is pivotally connected at 132 to the pull rod or link 134 which is afforded pivotal connection at 136 to the upper end of the adjacent live truck lever 14. The live and dead cylinder levers 110 and 124 may be afforded slidable support in the usual manner from support brackets 138, 138 mounted on the truck frame.

In operation of the brake rigging shown in the bottom half of Figure 1, the piston rod 106 moves to the left, whereby the live cylinder lever 110 is moved in a clockwise direction about the pivot point 112, the pull rod 114 causing the dead cylinder lever 124 to move in a counterclockwise direction about the pivot point 128. Through its connection to the associated cylinder lever, each live truck lever is caused to pivot about the pivot point 30, whereby the associated friction shoe 54 is engaged with the periphery of the adjacent wheel and at substantially the same time by means of the pull rod 28 the associated dead

truck lever is caused to move about its pivot point 18, whereby the associated equalizer lever 68 is urged against the adjacent bell crank levers 78, 78 to urge the shoes 82, 82 against the inboard and outboard surfaces of the adjacent wheel. It may be noted that in the event of relative lateral movement between the wheel and axle assemblies 12, 12 and the truck frame 2, the equalizer levers 68, 68 will rock on the arcuate ends of the bell crank levers 78, 78 to afford equalized pressure by the shoes 82, 82 against the wheels.

It will be understood that an object of my invention is to provide composition friction shoes 82, 82 and an iron friction shoe 54 for association with each wheel, whereby advantage may be taken of the combination of torque characteristics of composition and iron braking material acting against the iron wheel. However, it will be understood that all of the shoes 82, 82 and 54 may be iron or all may be composition, if desired. It will also be apparent that by means of the brake arrangement associated with each wheel, said wheel will be afforded equalized heating by the associated shoes, thus tending to prevent cracks in the wheel from thermal stresses resulting from braking forces acting thereon.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. In a brake arrangement, a vehicle frame, a supporting wheel and axle assembly comprising an axle with wheels thereon, brake beams at opposite sides of said assembly, dead truck levers fulcrumed at their upper ends from said frame, said levers being pivotally connected intermediate their ends to one of said beams, and said levers being operatively associated at their lower ends with friction means, live truck levers connected at their lower ends to the other of said beams, friction shoes supported by the last-mentioned beam for engagement with the peripheries of said wheels, pull rods pivotally connected to the live levers intermediate their ends and pivotally connected to the first-mentioned beam, power means operatively associated with the live levers, said friction means comprising friction shoes adapted to engage the inboard and outboard surfaces of each wheel, bell crank levers engaged at corresponding ends with said shoes, and an equalizer lever in abutment with opposite corresponding ends of said bell crank levers, a fulcrum member hung from said frame and affording fulcrums for said bell crank levers intermediate their ends, said members also affording slidable support for said equalizer lever, and a connection between said equalizer lever and the lower end of the associated dead lever.

2. In a brake arrangement, a vehicle frame, a supporting wheel and axle assembly comprising an axle with wheels thereon, brake beams at opposite sides of said assembly, dead truck levers fulcrumed at their upper ends from said frame, said levers being pivotally connected intermediate their ends to one of said beams, and said levers being operatively associated at their lower ends with friction means, live truck levers connected at their lower ends to the other of said beams, friction shoes supported by the last-

mentioned beam for engagement with the peripheries of said wheels, pull rods pivotally connected to the live levers intermediate their ends and pivotally connected to the first-mentioned beam, and power means operatively associated with the live levers, said friction means comprising an equalizer lever, means on the frame affording slidable support therefor, bell crank levers operatively associated with said equalizer lever and carrying friction shoes for engagement with inboard and outboard surfaces on the adjacent wheel, and an operative connection between said equalizer lever and the adjacent dead truck lever.

3. In a brake arrangement, a truck frame, a supporting wheel and axle assembly comprising an axle with wheels mounted thereon, live and dead truck levers at opposite sides of each wheel, the dead truck levers being pivotally fulcrumed at their upper ends from said frame, a brake beam pivotally connected to the dead levers intermediate their ends, said beam extending above the axle level, a brake beam extending below the axle level, operatively associated with the lower ends of said live levers, and carrying friction means for engagement with said wheel, friction means operatively associated with the dead levers and adapted for engagement with said wheels, pull rods connecting the first-mentioned beam to said live levers intermediate their ends, and power means operatively associated with said live levers, said last-mentioned friction means comprising friction shoes at inboard and outboard sides of each wheel.

4. In a brake arrangement, a vehicle frame, a supporting wheel and axle assembly comprising an axle with wheels thereon, brake beams at opposite sides of said assembly, dead truck levers fulcrumed at their upper ends from said frame, said levers being pivotally connected intermediate their ends to one of said beams, and said levers being operatively associated at their lower ends with friction means adapted to engage inboard and outboard surfaces on said wheels, live truck levers connected at their lower ends to the other of said beams, friction shoes supported by the last-mentioned beam for engagement with the peripheries of said wheels, pull rods pivotally connected to the live levers intermediate their ends and pivotally connected to the first-mentioned beam, and power means operatively associated with the live levers.

5. In a brake arrangement, a vehicle frame, a supporting wheel and axle assembly comprising an axle and a member rotatable therewith, friction shoes for engagement with opposite sides of said member, bell crank levers connected at corresponding ends to respective shoes, means suspended from said frame and affording a fulcrum for said levers intermediate their ends, an equalizer lever abutting the opposite corresponding ends of said bell crank levers, means affording slidable support for said equalizer lever, and actuating means for urging said equalizer lever against said opposite ends whereby said shoes are engaged with said member, said bell crank and equalizer levers being disposed in a plane diagonal with respect to the horizontal.

6. In a brake arrangement, a vehicle frame, a supporting wheel and axle assembly comprising an axle and a member rotatable therewith, friction shoes for engagement with opposite sides of said member, bell crank levers connected at corresponding ends to respective shoes, means suspended from said frame, and affording a fulcrum

for said levers intermediate their ends, an equalizer lever abutting the opposite corresponding ends of said bell crank levers, means affording slidable support for said equalizer lever, actuating means for urging said equalizer lever against said opposite ends whereby said shoes are engaged with said member, and resilient release means connected to said opposite corresponding ends and to said frame.

10 7. In a brake arrangement, a truck frame, a supporting wheel and axle assembly comprising an axle with wheels mounted thereon, live and dead truck levers at opposite sides of each wheel, brake beams pivotally connected to corresponding truck levers at opposite sides of the truck, friction means carried by one of said beams for engagement with the wheels, friction means actuated by the levers associated with the other beam, the last-mentioned friction means also being adapted to engage the wheels, pull rods pivotally connecting the last-mentioned beam to the levers associated with the first-mentioned beam, and power means operatively associated with the live levers, said last-mentioned friction means comprising friction shoes at inboard and outboard sides of each wheel.

15 8. In a brake arrangement, a truck frame, a supporting wheel and axle assembly comprising an axle with wheels mounted thereon, live and dead truck levers at opposite sides of each wheel, a brake beam connecting the dead levers, a brake beam hung from the frame, and carrying friction means for engagement with the wheels, connections between the live levers and the last-mentioned beam, pull rods pivotally connected to the first-mentioned beam and to the live levers, friction means actuated by the dead levers and formed and arranged for engagement with radial faces on said wheels, and operating means associated with the live levers, said last-mentioned friction means comprising a friction shoe spaced axially of each wheel and engageable therewith during a braking operation.

20 9. In a brake arrangement, a vehicle frame, a supporting wheel and axle assembly comprising an axle and a concentric member rotatable therewith, brake shoes for engagement with opposite sides of said member, bell crank levers connected at corresponding ends to respective shoes and at opposite corresponding ends to actuating means, and a fulcrum for said levers intermediate the ends thereof, said bell crank levers being disposed in a plane diagonal with respect to the horizontal, said actuating means comprising an equalizer lever bearing at opposite ends thereof against arcuate surfaces on said opposite corresponding ends.

25 10. In a brake arrangement, a vehicle frame, a supporting wheel and axle assembly comprising an axle and a concentric member rotatable therewith, brake shoes for engagement with opposite sides of said member, bell crank levers connected at corresponding ends to respective shoes and at opposite corresponding ends to actuating means, a fulcrum for said levers intermediate the ends thereof, and resilient release means connected to said frame and to said opposite corresponding ends, said actuating means comprising an equalizer lever extending above said resilient means and bearing against abutment surfaces on said opposite corresponding ends.

30 11. In a brake arrangement, a vehicle frame, a supporting wheel and axle assembly comprising spaced wheels, live and dead truck levers at opposite sides of said assembly, beams extending

transversely of said frame and connected respectively to corresponding live and dead truck levers, friction means supported by one of said beams for engagement with the peripheries of said wheels, pull rods connecting the live truck levers to the other of said beams, said live levers being connected to said first-mentioned beam, and friction means operatively associated with the dead levers, said last-mentioned friction means being formed and arranged for engagement with inboard and 10 outboard surfaces on said wheels.

12. In a brake arrangement, a vehicle frame, a supporting wheel and axle assembly comprising spaced wheels, a brake beam extending transversely of said frame and carrying friction means for engagement with the peripheries of said wheels, friction means for engagement with inboard and outboard sides of said wheels, and an operative connection between said beam and said last-mentioned friction means.

13. In a brake arrangement, a vehicle frame, a supporting wheel and axle assembly comprising spaced wheels, a brake beam extending transversely of said frame and carrying friction means for engagement with the peripheries of said wheels, friction means for engagement with inboard and outboard sides of said wheels, and an operative connection between said beam and said last-mentioned friction means, said operative connection comprising interconnected live and dead truck levers at opposite sides of said assembly.

14. In a brake arrangement, a vehicle frame, a supporting wheel and axle assembly comprising spaced wheels, a brake beam extending transversely of said frame and carrying friction means for engagement with the peripheries of said wheels, friction means for engagement with inboard and outboard sides of said wheels, and an operative connection between said beam and said last-mentioned friction means, said operative connection comprising live levers connected to said beam, dead levers operatively associated with said last-mentioned friction means, and means connecting said live levers to said dead levers.

15. In a brake arrangement, a vehicle frame, a supporting wheel and axle assembly comprising spaced wheels, a brake beam extending transversely of said frame and carrying friction means for engagement with the peripheries of said wheels, friction means for engagement with inboard and outboard sides of said wheels, and an operative connection between said beam and said last-mentioned friction means, said operative connection comprising live levers connected to said beam, dead levers operatively associated with said last-mentioned friction means, and means connecting said live levers to said dead levers, said last-mentioned means comprising a beam extending transversely of the frame and pivoted to said dead levers, and pull rods connected to said last-mentioned beam and to said live levers.

16. In a brake arrangement for a wheel, a beam at one side thereof carrying friction means for engagement with the peripheral surface of said wheel, friction means for engagement with a radial surface of said wheel, and operating means for said beam and said last-mentioned friction means comprising interconnected live and dead levers operatively associated therewith, said levers being disposed at opposite sides of the axis of said wheel.

17. In a brake arrangement for a railway car truck, a truck frame, a supporting wheel and axle assembly comprising a wheel, a fulcrum casting

hung from said frame adjacent said wheel, bell crank levers fulcrumed intermediate their ends from said casting and carrying friction means at their adjacent corresponding ends for engagement with inboard and outboard surfaces of said wheel, an equalizer lever slidably supported from said casting and bearing against the opposite corresponding ends of said bell crank levers, and actuating means for moving said equalizer lever toward said wheel whereby said friction means are frictionally engaged therewith.

18. In a brake arrangement for a railway car truck, a truck frame, a supporting wheel and axle assembly comprising a wheel, a fulcrum casting hung from said frame adjacent said wheel, bell crank levers fulcrumed intermediate their ends from said casting and carrying friction means at their adjacent corresponding ends for engagement with inboard and outboard surfaces of said wheel, an equalizer lever slidably supported from said casting and bearing against the opposite corresponding ends of said bell crank levers, actuating means for moving said equalizer lever toward said wheel whereby said friction means are frictionally engaged therewith, and resilient release means connected to said opposite corresponding ends and to adjacent portions of said casting.

19. In a brake arrangement for a railway car truck, a truck frame, a supporting wheel and axle assembly comprising a wheel, a fulcrum casting hung from said frame adjacent said wheel, bell crank levers fulcrumed intermediate their ends from said casting and carrying friction means at their adjacent corresponding ends for engagement with inboard and outboard surfaces of said wheel, an equalizer lever slidably supported from said casting and bearing against the opposite corresponding ends of said bell crank levers, and actuating means for moving said equalizer lever toward said wheel whereby said friction means are frictionally engaged therewith, said actuating means comprising a substantially vertical dead truck lever operatively connected to said equalizer lever.

20. In a brake arrangement for a wheel, a brake beam carrying friction means for engagement with the periphery of said wheel, friction means for engagement with radial surfaces on opposite sides of said wheel, a lever connected to said beam, a lever operatively associated with said beam, means interconnecting said levers, and actuating means associated with said levers.

21. In a brake arrangement for a wheel, a brake beam carrying friction means for engagement with the periphery of said wheel, friction means for engagement with radial surfaces on opposite sides of said wheel, a lever connected to said beam, a lever operatively associated with said last-mentioned friction means, means interconnecting said levers, and actuating means associated with said levers, said interconnecting means comprising a beam pivoted to said second-mentioned lever and a pull rod connected to said last-mentioned beam and to said first-mentioned lever.

22. In a brake arrangement, a vehicle frame, spaced supporting wheel and axle assemblies, each comprising an axle and spaced wheels, friction means for engagement with the peripheries of said wheels, friction means for engagement with inboard and outboard surfaces thereof, and actuating means for said friction means comprising brake beams associated therewith and ex-

tending transversely of said frame at opposite sides of each wheel and axle assembly, interconnected live and dead truck levers connected to the beams associated with each assembly, and operating means associated with said live levers.

23. In a brake arrangement, a vehicle frame, spaced supporting wheel and axle assemblies, each comprising an axle and spaced wheels, friction means for engagement with the peripheries of said wheels, friction means for engagement with inboard and outboard surfaces thereof, and actuating means for said friction means comprising brake beams associated therewith and ex-

tending transversely of said frame at opposite sides of each wheel and axle assembly, interconnected live and dead truck levers connected to the beams associated with each assembly, and operating means associated with said live levers, said operating means comprising a power cylinder device supported on said frame, interconnected live and dead cylinder levers connected to opposite ends of said device, and an operative connection between each cylinder lever and the adjacent live truck lever.

CARL E. TACK.
